UNITED STATES PATENT OFFICE.

HENRY G. JOHNSON, OF EAST HAMPTON, CONNECTICUT, ASSIGNOR TO SUMMIT THREAD COMPANY, OF EAST HAMPTON, CONNECTICUT, A CORPORATION OF MAINE.

UNIVERSAL WINDER HEAD.

1,414,514.

Specification of Letters Patent. Patented May 2, 1922.

Application filed March 3, 1921. Serial No. 449,579.

To all whom it may concern:

Be it known that I, HENRY G. JOHNSON, a citizen of the United States, residing at East Hampton, in the county of Middlesex 5 and State of Connecticut, have invented new and useful Improvements in Universal Winder Heads, of which the following is a specification.

This invention relates to machines for winding thread on spools, and has particular reference to means somewhat in the nature of an attachment to what are known as universal winders, whereby a spool or tube having a head at but one end can be wound 15 with the thread in layers.

The object of the invention is to provide means which will so lay the wound thread that the surface of the layers at the end of the spool or tube having no head will be 20 tapered or beveled, whereby the thread is unlikely to fall off at that end, and the thread can be freely drawn from that end without encountering any spool head.

The object mentioned is accomplished by 25 automatically effecting a gradual longitudinal shifting of the rotating spool, and the traverse of the thread guide or eye relatively to each other. In the illustrated embodiment of the invention, the thread guide, during operation, has a traverse of a given 30 length, so that the number of coils in all the layers are always the same for a given length of spool or tube. As the layers of thread are superposed one upon the other, 35 the thread guide is pushed away from the axis of the spool, by the increasing diameter of the windings, and this movement of the guide is utilized to gradually shift the relative positions of the spool and the traversing thread guide in the direction of the axis 40 of the spool. In the machine illustrated it is the spool which moves longitudinally.

With the above object in view, the invention consists in the mechanism substantially 45 as hereinafter described and pointed out in the claims.

Of the accompanying drawings forming a part of this specification,—

Figure 1 is an elevation of the machine, 50 omitting such parts as are well known in this type of mechanism.

Figure 2 is a top or plan view of the same, omitting the traversing cam which appears in Figure 1.

Figure 3 is a sectional view of the spool 55 mandrel and its supporting and carrying shaft.

Figures 4 and 5 are top and front views of the thread guide or button.

Figures 6, 7 and 8 are views similar to 60 portions of Figure 2, illustrating different positions of the parts when the spool is empty, partly filled, and filled, respectively.

The same reference characters indicate the same parts in all of the figures. 65

The thread guide 1 is carried by an arm 2 of a rod or bar 6 mounted to slide in a guideway of the swinging support 7. One face of the thread guide is beveled, as at 3, to substantially correspond with the angle 70 of the face of the head 4 of the spool 5. This beveling of the guide 3 is to enable the thread, which runs through the notch or eye 3^a, to be laid close to the spool head 4 (Figures 6, 7, and 8). The support 7 is pivotally 75 mounted on the jack shaft 8, by means of arms 7^a of the said support, and suitable counterbalancing devices, such as are usually employed in this type of winder, may be employed to exert a tendency to 80 press the guide 1 toward the spool.

Secured to the member 7 is a plate 9 having an upstanding pin 10 on which a block 11 is mounted. Slidably fitting a transverse bearing on the block 11 is an arm 12 of a 85 fitting 13, pivotally connected at 14 to the frame of the machine, as by a screw 15. Another arm 16 projects from the fitting 13, the two arms 12 and 16 practically constituting an elbow lever. A fitting 17 is adjustably secured on the arm 16 by a set screw 18, and has a vertical pin 19. A link 20 connects the pin 19 with a fitting 21, secured by a set screw 22 to a slide rod 23, mounted to reciprocate, but not rotate, in 95 bearing ears 24^a of a bracket 24 rigidly supported on short arms 25 by clamp clips 25^a. The arms 25 are secured in ears 26 of the frame of the machine by screws 27.

Rotatably mounted on the outer end of 100 the rod 23, is an externally threaded sleeve 28, held between collars 29, secured to the rod by set screws 30, said sleeve having a knurled portion 31 for convenience in rotating it. Mounted on and engaging the 105 threads of the sleeve 28 is the internally threaded hub 32 of an arm 33, forked at its outer end and engaging an annular groove.

34 in the spool mandrel 35. The mandrel is slidably mounted on the extended portions 36 of the main shaft 37, the driving connection between said shaft portion and the 5 mandrel being maintained by a key 38 and key-way 39 (Figure 3).

A belt pulley 40 mounted on the shaft 37 is adapted to be connected thereto to drive it by a suitable clutch mechanism, not necessary to illustrate, the engaging operation of the clutch being effected manually by a clutch lever 41 at one end of a clutch-operating shaft 42. The throwing off of the clutch is usually effected automatically, by 10 mechanism not necessary to illustrate, as it forms no part of this invention.

The shaft 37 also carries a pulley 43, connected by a belt 44, with a pulley 45 which, through suitable speed-reducing gearing in 20 the casing 46, drives the jack shaft 8 carrying the path cam 47. Said cam 47 engages a roll carried by a pin 48, which projects down from the slide 6.

In operation, an empty spool is secured 25 upon the mandrel by the tapered plug 49 acting in the usual way to expand the split portions of the mandrel, and at the start of the winding the thread guide 1 bears against the spool about as indicated by the 30 full lines in Figure 6, this being effected by the usual counterbalancing mechanism, not necessary to illustrate herein. During winding of the first layer the cam 47 effects a traverse of the slide 6, and its arm 2, to the 35 position indicated in Figure 1, carrying the guide 1 to about the position indicated by dotted lines in Figure 6. As the return layer is being wound the guide 1 bears on and rides along the first layer, resulting in swinging 40 the arm 2 and the support 7 back. The plate 9 and its pin 10, carried by the swinging support, transmits this motion through the elbow lever 12, 16, to the link 20, and through the latter to the slide rod 23 and the 45 fork arm 33, which latter effects a slight longitudinal movement of the mandrel and spool toward the right (Figure 2), or toward the outer end of the shaft 36. The parts are so proportioned that this longitudinal movement of the spool equals the diameter of the 50 thread being wound. As the winding progresses the thread guide is pushed farther and farther away from the axis of the spool, and the spool is shifted more and more to the right as shown by comparing Figures 6, 7, and 8, thus presenting a filled spool having the exposed end tapered or beveled. Preferably the angle of the bevel is at 45° to the axis of the spool, corresponding with a 55 similar angle of the inner face of the one spool head 4.

To secure the best results it is, of course, essential that the thread filling shall be compact. To this end it is important that the 60 parts of the machine are so proportioned and

70 relatively timed that the angle of the bevel at the exposed end shall be the same as that of the inner face of the spool head 4, whether that angle be just 45° or somewhat more or less.

The provision of the threaded sleeve 28 is to enable the yoke or fork arm 33 to be adjusted on or relatively to the slide 23 to accommodate spools having heads 4 of different thickness. 75

I claim:

1. In a winding machine of the character described, a rotary spool having a single head, a traversing thread-guide, and means controlled by the distance of the guide from the axis of the spool for automatically effecting a gradual shifting of the relative positions of the spool and thread-guide in the direction of the axis of the spool to wind the layers successively away from the headless end of the spool. 80

2. In a winding machine of the character described, a rotary and longitudinally movable spool provided with a single head having a cone-shaped inner face, a traversing thread-guide, and means controlled by the guide for effecting a gradual longitudinal movement of the spool in a direction to form the successive layers of thread with a cone-shaped outer end. 85

3. In a winding machine of the character described, a rotary and longitudinally movable spool mandrel, a traversing thread-guide having a laterally beveled face, and means controlled by the guide for effecting a gradual longitudinal movement of the mandrel as successive layers of thread are wound on the spool. 90

4. In a winding machine of the character described, a rotary and longitudinally movable spool having a single head, a thread-guide support movable toward and from the spool, a slide mounted on said support and carrying the thread-guide, means for reciprocating the slide, and connections between said support and the spool to effect a gradual longitudinal movement of the spool in a direction to form the successive layers of thread with a cone-shaped outer end. 105

5. In a winding machine of the character described, a rotary and longitudinally movable spool mandrel, a thread-guide support movable toward and from the mandrel, a slide mounted on said support and carrying the thread-guide, means for reciprocating the slide, and an elbow lever having an arm connected with the thread-guide support, and having its other arm connected with the spool mandrel. 110

6. In a winding machine of the character described, a rotary and longitudinally movable spool mandrel, a thread-guide support movable toward and from the mandrel, a slide mounted on said support and carrying the thread-guide, means for reciprocating 115

the slide, and connections between said support and the mandrel to control the longitudinal positions of the mandrel, means being provided to adjust said connections.

- 5 7. In a winding machine of the character described, a rotary and longitudinally movable spool mandrel, a thread-guide, a swinging member having a guideway for the thread-guide, an elbow lever having an arm 10 connected with said swinging member, a slide parallel with the spool mandrel and connected with the other arm of the elbow lever, and connections between said slide and the spool mandrel.
- 15 8. In a winding machine of the character described, a rotary and longitudinally movable spool mandrel, a thread-guide, a swinging member having a guideway for the thread-guide, an elbow lever having an arm 20 connected with said swinging member, a slide parallel with the spool mandrel and connected with the other arm of the elbow

lever, and a forked arm carried by the slide, the said mandrel having an annular groove with which the fork of said arm is engaged. 25

9. In a winding machine of the character described, a rotary and longitudinally movable spool mandrel having an annular groove, a swinging member having a guideway, a slide mounted in said guideway and carrying a thread guide, an elbow lever having one arm connected with the swinging member, a second slide mounted to reciprocate in fixed bearings and connected with the other arm of the elbow lever, an externally 30 threaded sleeve rotatably mounted on said second slide, and an arm having a threaded hub engaging the threads of said sleeve, the said arm having a fork engaging the annular groove of the mandrel. 35

In testimony whereof I have affixed my signature.

HENRY G. JOHNSON.
